UNITED STATES PATENT OFFICE.

MARTIN FOX, OF CHICAGO, ILLINOIS.

CONCEALED HINGE.

Application filed June 15, 1925. Serial No. 37,010.

This invention relates particularly to a hinge for connecting table leaf sections, although of course it may have a more general use wherever applicable. Among the 5 objects of the invention are: to provide a hinge made entirely of metal stampings; to provide a hinge of this kind which may be secured to the adjacent ends of two leaves to be connected which will make them abut 10 closely and render the hinge invisible; and to provide a hinge of this kind in which a projection of one portion of the hinge will act as a levelling support for the two leaf sections connected by the hinge.

15 In the accompanying drawing Fig. 1 is a side elevation showing the hinge in folding or closed position; Fig. 2 is a side elevation showing the hinge in open or extended position; Fig. 3 is a plan view of the hinge in 20 open position; and Fig. 4 is a sectional view taken on the line 4—4 of Fig. 3.

The hinge proper comprises two members 1 and 2 somewhat similar and adapted to be secured by screws 3 to the adjacent edges of 25 the hinged members or leaves 4. The hinge members 1 and 2 are angular in cross section, as shown more clearly in Fig. 4, and has an upstanding portion 5 or 6 which is usually disposed at the side of one of the 30 leaves to be connected, the base or other portion being secured to the bottom of the leaf. The leaf itself may be cut away or countersunk to accommodate the base or upstanding part of the hinge so that the hinge 35 parts will be flush with the side and end of the leaves. The upstanding parts 5 and 6 are inclined upwardly and outwardly toward their adjacent edges, as shown in Fig. 4, and in these parts are slots 7 and 8.

40 From the base of the hinge part 2 there is a projection 9 which extends into a corresponding recess 10 in the other hinge part 1, and also extends across the meeting line between the hinge parts and between the 45 leaves to which the hinge parts are attached. The object of this projection 9 is to evenly support the two leaf sections 4 when they are in open position so that they will be flush on top when they are in open position, even though the hinge parts themselves 50 may not be exactly or accurately positioned.

In order to connect the hinged parts 1 and 2 there are two similar levers 11 and 12, one pivotally connected at one end to the extremity of the upstanding portion 5 and having headed projections at its other end 55

movable in the slots 8 of the other hinge member, and the other lever 12 being pivoted to the upstanding portion 6 of the hinge member 2 and having its other end with a 60 headed projection slidable in the slot 7 of the hinge member 1. These levers 11 and 12 are curved substantially in the form of a semi-circle and cross each other at an angle where they have a common pivot 13. The 65 result is that when these leaves 11 and 12 are in one position, as limited by the slots 7 and 8, the hinge members are spaced apart, as shown in Fig. 1, and when they are moved so that they are at the other ends of the 70 slots 7 and 8, the hinge members 1 and 2 are closely abutting with the leaf sections 4 in alinement, as shown in Fig. 2. In the first position the hinge members project from the ends of the leaf members, and in 75 the second position they project below the junction of the leaf members. At no time do they engage the abutting ends of the tops of the leaf sections and when in extended form, as shown by Fig. 2, the hinges 80 and the parts thereof are invisible from the top of the leaf.

These hinge parts are made entirely of stamped sheet metal and are preferably formed with rounded raised portions 14 surrounding the screw holes which make countersunk portions for the screw heads. At the bending line between the base and the upstanding portion there is a rounded groove 15 instead of a sharp bend which 90 strengthens the hinge member and prevents cracking or breaking the hinge member in its formation. One of the hinge members is formed with a projection 16 to which the lever 11 is pivoted and the other end of 95 the lever is formed with an offset 17 so that the levers 11 and 12 will be in proper position and relation to pass each other.

With this construction it is obvious that table leaf sections or any two members may 100 be connected for a hinging movement of approximately 180° and that when the members are in open position the hinge will be entirely invisible from the top thereof, all of the parts being covered or concealed by 105 being flush with the surfaces, or being inserted in recesses or slots made in the under sides of the leaf sections for the purpose of receiving the hinge parts.

I claim:

1. The combination with a pair of sectionally angular hinge members adapted for

110

- attachment to the adjacent corners of a pair of members to be connected, the corresponding angular parts being formed with inclined slots, and a pair of pivotally connected 5 links each of which is pivoted to one of the angular parts in line with the slot thereof and has a pivoted sliding connection with the slot of the other member the links extending below the confines of the members 10 when they are in aligning position.
2. In a concealed hinge, a pair of sectionally angular plates for attachment to the underside of members to be connected, and having an upright slotted portion connected 15 to the base portion by an offset rounded groove, and links having a pivotal connection

with each other and a pivotal and sliding connection with both of the plates.

3. In a hinge of the class described, a pair of sectionally angular plates each having a 20 base and a slotted portion at right angles thereto and adapted to abut on a predetermined line at the ends of the plates, there being a projection from the base of one of the plates and a corresponding recess in the 25 base of the other plate, the projection of which overlaps the normal abutting line of the plates, and means forming a pivotal and sliding connection between the slotted portions of the plates.

MARTIN FOX.
